UNITED STATES PATENT OFFICE

JOHN LITTLE, OF PLAINFIELD, NEW JERSEY, ASSIGNOR TO WOOD NEWSPAPER MACHINERY CORPORATION, OF NEW YORK, N. Y., A CORPORATION OF VIRGINIA.

CENTER CLIP

Application filed November 17, 1927. Serial No. 233,838.

This invention relates to a center clip for holding the plates on a printing cylinder at a point between two plates longitudinally located on the cylinder.

5 The principal object of the invention is to avoid the necessity for a very large hole ordinarily required when the clip is made removable as is necessary in this particular place; also to provide a clip made in two 10 halves, held in place by means located in one of them and projecting into the other and capable of being separated to enable each half to be removed separately, all co-operating to reduce the hole or opening ordinarily found 15 under the plate at this point, and thus avoiding a large area of plate unsupported at the rear.

Other objects and advantages of the invention will appear hereinafter.

20 Reference is to be had to the accompanying drawings in which

Fig. 1 is a plan of an intermediate clip formed in two parts according to this invention and showing the two parts separated and 25 ready for assembling or removal;

Fig. 2 is a similar view showing the two parts of the clip assembled and fixed in position;

Fig. 3 is a sectional view on the line 3—3 of 30 Fig. 2, showing in dotted lines, the plates in position;

Fig. 4 is a sectional view on the line 4—4 of Fig. 2;

Fig. 5 is a view similar to Fig. 1, showing 25 a modification;

Fig. 6 is a view similar to Fig. 2, showing the modification, and

Figs. 7 and 8 are sectional views on the lines 7—7 and 8—8 respectively of Fig. 6.

40 Printing press plate cylinders are provided with intermediate clips between the inner and outer plates at each end of the cylinder. It is necessary to make these clips removable from the cylinder readily for the purpose

45 of enabling the pressman to apply single plates of two-page width for double page spreads. This necessitates the provision of a hole of a large size cut out of the cylinder, thus removing a considerable portion of the

50 support under one of the printing plates.

This hole is considerably larger than the width of the groove in which the clips slide, and as the plate is unsupported under this area it is considered a drawback to good printing.

55 The main object of this invention is to avoid this hole, leaving only the groove in which the clip is supported. For this purpose, referring to the first four figures, it will be seen that the plate cylinder 10 is provided 60 with a groove 11 extending longitudinally for receiving the intermediate clip. This groove is undercut on the sides 12 below. According to this invention it does not have to be enlarged to provide any hole by which the 65 clips are removed.

The way I have shown in these four figures for securing this result is to form the clip in two halves 13, these halves being rights and lefts, and each of them having a ledge 14 projecting into the undercut groove 12 on one side. The two clips extend clear across the groove as shown in the drawings, and engage each other at the center. Each one is provided with a dove-tail 15 extending at 75 right angles to the groove 11, and projecting from the center line outwardly.

In assembling the parts for the plates, these 80 clips are moved along until these two dove-tails register, as shown in Fig. 2, and then two screws 16 are inserted. Each screw has a screw-hole in one piece and each one has a head which projects beyond its own half into a recess 17 in the other half. In this way the 85 heads of these screws secure accurate register and prevent the two halves from moving longitudinally either to the point of separation or to the point of getting out of actual registration. The dove-tail 15 accurately holds the plate on each side, as indicated in dotted 90 lines in Fig. 3, and the parts are held firmly in position by the screws 16.

To remove the clips, the two screws 16 are taken out, or at least unscrewed so that the 95 heads come out of the recesses 17, and then one of the parts can be slid along so that they are in the relative positions indicated in Fig. 1. Now both parts can be removed and replaced at will.

The same principle can be carried out in 100

other forms, as for example, in the form shown in Figs. 5, 6, 7 and 8. This construction is similar to the one shown in the first four figures, except that the top of the clip is in one piece and it is only at the bottom 5 that the divisional piece 20 is provided. This latter piece has a projecting portion 21 that extends into the undercut portion of the groove and holds this side of the clip in position. This member 20 also has a projecting 10 horizontal tongue 22 at the bottom, and a tongue 23 at the top projecting into recesses or grooves in the main portion of the clip. The two parts are held together by a single 15 screw 26 which passes through the top of the clip into the tongue 22 and holds the parts firmly together. When this screw is removed, the two parts, of course, are separated and the lower one 20 can be pushed out at the 20 bottom as indicated in Fig. 5. Then there is no projecting member on the top part of the clip to prevent its being raised out of the groove in the plate.

It will be seen, therefore that no hole or 25 opening is required except the groove in which the clip is located. This groove has to be employed anyway. The clips are removed readily and are solidly located in position after adjustment and the fastening up 30 of the screws. There is no material area of the printing plate that is unbacked. Therefore the printing is uniform over its entire surface.

Although I have illustrated and described 35 only two forms of the invention I am aware of the fact that other modifications can be made therein by any person skilled in the art without departing from the scope of the invention as expressed in the claims.

40 Therefore I do not wish to be limited to the exact form shown, but what I do claim is:—

1. An intermediate plate clip for a printing cylinder consisting of a plurality of parts, 45 each having means for holding it in an undercut groove when the parts are assembled, said parts being separately movable to release the parts from each other.

2. An intermediate plate clip consisting of 50 two relatively slidable parts adapted to be held in a groove in a printing cylinder, whereby either one can be moved longitudinally away from the other to release them both.

3. An intermediate plate clip consisting of 55 two parts, each having an outer projection at the lower edge for fitting in two opposite undercut grooves, a dove-tail on each of said parts for holding the ends of the two adjacent plates, and means for securing the two parts 60 together in a groove in the printing cylinder.

4. As an article of manufacture, an intermediate plate clip consisting of two parts, the two parts together being adapted to fill a groove in a printing plate cylinder, a screw 65 located in one part and engaging the other

to hold the two parts together, and means on each part for holding that part in radial position in the groove when they are secured together, said parts being slidable longitudinally in the groove past each other when the 70 screw is removed.

5. As an article of manufacture, an intermediate plate clip for a printing cylinder comprising two parts, each part having a main body provided with an outer projection at the bottom and a dove-tail located transversely at the top and extending outwardly from the center thereof, whereby the two parts are adapted to come together at the center to form a complete clip, a screw 75 threaded in each part and having a head projecting over into the other part across the center, each part having an arcuate recess for receiving the head on the screw of the other part to prevent longitudinal separation when 80 the screws are in position.

6. The combination with a printing cylinder having a groove extending longitudinally and provided with undercut recesses at its opposite sides, of a plate clip having a dove-tail on top for engaging the beveled edges of two adjacent plates on the cylinder, said plate clip consisting of two parts, each part having an outwardly extending projection entering the undercut groove, and a screw for holding 90 the two parts together firmly, whereby when the screw is removed the two parts can be separated in the groove longitudinally.

7. An intermediate plate clip for a printing cylinder consisting of a plurality of parts, 100 each having means for holding it in an undercut groove when the parts are assembled, said parts being separately movable with respect to each other to release the parts from each other in a direction along the groove.

In testimony whereof I have hereunto affixed my signature.

JOHN LITTLE.
